UNITED STATES PATENT OFFICE.

EDWARD K. MCNEAL, OF FORESTVILLE, NEW YORK.

ERASURE-RECEIVING ATTACHMENT FOR TYPEWRITERS.

Application filed December 11, 1923. Serial No. 680,001.

To all whom it may concern:

Be it known that I, EDWARD K. MCNEAL, a citizen of the United States, residing at Forestville, in the county of Chautauqua and State of New York, have invented a new and useful Improvement in Erasure-Receiving Attachments for Typewriters, of which the following is a specification.

This invention relates to erasure receptacles for use in connection with typewriting machines.

It is well known that much damage is done to typewriting machines due to the fact that particles of grit, rubber, paper, glass or other substances, (these particles being herein referred to as "erasures") drop on various parts of the machine, as a result of erasing parts of the work, and find their way into bearings or other parts of the machine, where they cause excessive wear. Erasure shields have heretofore been supplied with parts adapted to collect the erasures, but these shields were always made detached from the machine and would readily become lost or mislaid, or would not be used by an operator since it requires some time to find and to place these shields in position on the work.

The objects of this invention are to provide an erasure receptacle that can be attached to the machine in a position to receive the erasures, thereby eliminating the delay incident to using receptacles which cannot be attached to a machine; also to provide an erasure receiving attachment for typewriters which can be readily attached to a machine and detached therefrom for removing the erasures accumulated therein; also to provide an erasure receiving attachment of this kind which has the usual scale formed thereon, to enable an operator to readily position papers or other work on the machine; also to improve the construction of devices of this kind in other respects herein-after specified.

In the accompanying drawings, Figs. 1 and 2 are a fragmentary front elevation and a top plan view respectively of a typewriting machine having erasure receiving attachments embodying my invention mounted thereon.

Fig. 3 is a transverse section thereof on line 3—3, Fig. 1.

Fig. 4 is a front elevation of an erasure

receiving attachment detached from the machine. 55

Fig. 5 is a front elevation of the attaching bracket or part for holding the receptacle in its operative position.

Fig. 6 is a view showing the blank from 60 which the receptacle is formed.

Fig. 7 is a perspective view of a typewriter platen with an erasure receiving attachment of another construction in operative relation thereto. 65

Fig. 8 is a top plan view of the attachment illustrated in Fig. 7.

Fig. 9 is a transverse sectional view of the attachment on line 9—9, Fig. 7.

Fig. 10 is a top plan view of an erasure 70 receiving attachment of modified form applied to a different model of typewriter.

Fig. 11 is a vertical sectional view of the erasure receiving attachment illustrated in Fig. 10, the section being taken on line 11— 75 11, Fig. 10.

Fig. 12 is a fragmentary perspective view of another modified form of erasure receiving attachment applied to another model 80 of typewriter.

In order to prevent the erasures dropping into the mechanism of typewriting machines, I have provided a receptacle which is mounted on the typewriter while the same is in use and in which the erasures are caught 85 and accumulate and which can be emptied. For this purpose the receptacle is constructed so that it can be quickly attached to and detached from the typewriter and held in position thereon so that all the erasures made 90 are caught by the receptacle before they have a chance to drop into the working mechanism of the machine.

In the embodiment of my invention shown in Figs. 1 to 6, an erasure receptacle is provided which may be attached to typewriting machines of the Underwood type, having a platen A, ribbon spools B, a type guide C and a part of a ribbon vibrating mechanism D. E represents the usual guide segment for the type bars, which is provided with a plurality of slots e in which the pivoted ends of the type bars operate. 95

As illustrated in Figs. 1 to 6, the typewriter attachment comprises a trough 15, 105 which is preferably formed or stamped of sheet metal and in the construction shown is substantially V-shaped in cross section,

having a front wall 16 and a rear wall 17. The ends of the trough may be closed by means of end walls 18 and 19, which extend laterally from a depending flange 20, which is formed by bending the metal along the line 21 shown in Fig. 6, forming a bent rear edge at the upper rear portion of the trough. The side walls 18 and 19 in addition to closing the ends of the front and rear walls of the receptacle also reinforce the receptacle in such a manner as to prevent bending of the same about the rear edge 21. The flange 20 is provided at one side thereof with a downwardly extending portion 22 which is adapted to slidably engage a holder or socket 25 secured on the frame of the typewriting machine. This socket may be of any suitable or desired construction, that shown including a plate having ears or projections 26 which are bent or turned over in a direction parallel to the plate and spaced at a distance therefrom so as to permit the insertion of the downwardly extending portion 22 on the receptacle. The socket member or bracket 25 is provided near the lower portion thereof with holes or perforations 27 through which screws 28 may pass into the segment E for holding the socket in place. These screws are ordinarily employed for holding the scales shown in Figs. 7-9 in their operative positions on the machine, and in order to apply my erasure receptacles to the machine, the scales are removed and the supporting brackets 25 are secured to the machine in place of the scales by means of the screws 28, the holes 27 in the brackets being of larger size than the screws so as to permit adjustment of the brackets. The erasure receptacles are then removably held on the brackets by means of the ears 26 thereof and whenever the receptacles are filled with erasures it is only necessary to pull them upwardly out of engagement with the brackets and empty them, whereupon they can be replaced on the brackets.

In order to enable an operator to readily position a piece of work in the machine, the upper edges 21 of the erasure receptacles are positioned at the same elevation as the scales ordinarily used on the machine, and if desired, graduations 30 may be placed on the inner and visible face of the rear wall of the receptacles adjacent to the upper edge 21 thereof. When provided with these graduations the receptacles take the place of the usual scales supplied with the Underwood machine.

The downwardly extending flange 20 and the extension 22 thereof, or the brackets 25 or both, are preferably made of resilient material, so that the upper edge 21 of each erasure receptacle is yieldingly pressed against the work on the platen. This enables the erasure receptacles to receive all

of the erasures and also enables the receptacles to readily adapt themselves for different thicknesses of work placed in the typewriter. The receptacles may be made of any suitable or desired shape to best adapt themselves to the machines on which they are used, and for this purpose the outside walls 19 thereof are curved as shown in Fig. 2 to clear the ribbon spools B and still extend along the platen as far as possible. 75

In the construction shown in Figs. 7 to 9, an erasure receiving attachment is provided which can be held on an Underwood typewriter by means of the usual scales F of the machine. With this construction it is not necessary to remove the scales from the machine as in the constructions shown in Figs. 1 to 6, and the spring f of the scale serves to hold the receptacle yieldingly against the platen. 32 represents the trough which may be of any suitable or desired construction and which has on the rear wall thereof a downwardly turned lip or flange 33, which is adapted to slip over the upper edge of the scale F and thus hold the receptacle in place. In order to take the place of the graduations on the scale, the inner face of the rear wall of the receptacle 32 is provided with graduations 34. This receptacle can be easily removed from the upper edge of the scale for emptying and can be easily replaced thereon. 90

The erasure receiving attachment shown in Figs. 10 and 11 is adapted for use on another type of machine, and in this case a trough 35 is mounted on one end of an arm 36. The other end of the arm is mounted on a clip or bracket 37 which may be hooked over or otherwise suitably secured to a ribbon easing B'. A coil spring 38 engages the arm 36 and the clip 37 and is adapted to normally force the arm into the position shown in dotted lines in Fig. 10. A second coil spring 40 is provided adjacent to the pivot connecting the other end of the arm 36 and the receptacle 35 and this spring is adapted to normally force the receptacle into a position in which the side thereof is forced against the shoulder 41 of the arm, see particularly Fig. 11, in which position the receptacle is held substantially parallel to the typewriter platen while out of engagement therewith, as shown in dotted lines in Fig. 10. In using the receptacle shown in Figs. 10 and 11, the receptacle is moved into an operative position relatively to the platen by moving the outer end of the arm 36 toward the platen so that the rear edge 105 of the trough carried on the end thereof rests flatly against the paper supported on the platen, as illustrated in full lines in Fig. 10. When the erasure has been made, the receptacle is released by the operator and then automatically returns to its normal 110 position, shown in dotted lines in Fig. 10. 115

The downwardly extending flange 20 and the extension 22 thereof, or the brackets 25 or both, are preferably made of resilient material, so that the upper edge 21 of each erasure receptacle is yieldingly pressed against the work on the platen. This enables the erasure receptacles to receive all 120

due to the action of the springs 38 and 40. The clip 37 is made readily removable from the ribbon casing, preferably by providing the same with a flange somewhat similar to 5 the lip or flange 33, engaging the upper edge of the ribbon casing and when the receptacle is filled, the clip is moved out of engagement with the ribbon casing so that the receptacle can be removed from the machine 10 and emptied, whereupon the clip can readily be replaced on the ribbon casing.

In Fig. 12 another form of receptacle is illustrated, which comprises a shallow trough 42 conforming in outline to the top 15 of the frame G of the typewriter to which it is attached. The inner end of the trough is slightly turned up, as illustrated at 43, and the lower end of the trough has an additional channel 44 formed thereon, in 20 which the erasures finally collect after dropping upon the receptacle. This form of receptacle is adapted to be supported below the platen and not in front of the same, as are the receptacles illustrated in the other 25 figures. In order to hold the receptacle shown in Fig. 12 on the machine, a clip 45 is formed on the outer end thereof, which clip is adapted to slide over an edge of the frame to yieldingly hold the receptacle in 30 its operative position. The clip can be readily disengaged from the machine by forcing it out of engagement with the edge of the frame thereof, so that the entire receptacle can be withdrawn from under the 35 platen and the erasures collected therein emptied.

The erasure receptacles are all described as made of sheet metal, but it will be understood that they may be made of any other 40 material. All of the receptacles described are mounted on the typewriter so that they are always in a position to be readily used and remain on the machine while the same is used for writing. Consequently if it 45 becomes necessary to use an eraser, the collecting of erasures to avoid their dropping into the parts of the machine where they may do damage, does not involve any loss of time or extra effort on the part of the 50 operator. The erasure receiving attachments are all so constructed that they can be easily removed from the machines for emptying the same and can be easily replaced.

55 I claim as my invention:

1. An attachment for typewriters comprising a receptacle adapted to receive material dropping from the work supported on the platen and means for supporting said receptacle on the typewriter in its operative position during the operation of said typewriter and relatively to which receptacle said platen may move during the operation 60 of the typewriter.

65 2. An attachment for typewriters com-

prising a receptacle adapted to receive erasures, and means for removably supporting said receptacle on said typewriter in its operative position during the operation of said typewriter.

70

3. An attachment for typewriters comprising a receptacle adapted to receive erasures, and means on said receptacle for removably supporting said receptacle on said typewriter in its operative position during the operation of said typewriter and in a position to permit said platen to move relatively to said receptacle during the operation of said typewriter.

75

4. A typewriter attachment for receiving erasures comprising a receptacle, means for mounting said receptacle on the frame of the typewriter in front of the platen with an edge of said receptacle movable into close proximity to the platen of the typewriter, to catch erasures dropping from the work supported by said platen.

80

5. An attachment for typewriters comprising a receptacle adapted to receive erasures, means mounted on the typewriter 90 in front of the platen for removably supporting said receptacle, and means for yieldingly pressing said receptacle toward the platen of the typewriter and for permitting said platen to move relatively to 95 said receptacle.

6. A typewriter attachment for receiving erasures from typewriters comprising a receptacle removably arranged on a typewriter, and a yielding support for said receptacle provided in front of the typewriter 100 platen.

7. A typewriter attachment for receiving erasures comprising a receptacle, a bracket provided on said typewriter in front of the 105 platen thereof, means for removably attaching said receptacle to said bracket, and means for yieldingly holding said receptacle against a typewriter platen.

8. An attachment for typewriters comprising a receptacle adapted to receive erasures, and means for supporting said receptacle on the typewriter in its operative position during the operation of said typewriter and in front of the platen thereof, 110 said means and said receptacle being detachably connected whereby said receptacle may be readily removed from said typewriter.

9. An attachment for typewriters comprising a receptacle adapted to receive erasures, and means for removably supporting said receptacle in its operative position during the operation of said typewriter and in front of the platen thereof to receive 115 erasures dropping from the work supported on said platen the platen being adapted to move relatively to said receptacle during the operation of the typewriter.

10. A device for receiving erasures from 120

125

125

130

typewriters comprising a receptacle, a bracket for supporting said receptacle, spring pressed means adapted to hold said receptacle against the platen of a typewriter, said receptacle being removably attached to said bracket.

11. An attachment for typewriters comprising a receptacle adapted to receive erasures and having a wall arranged in close proximity to the platen of the typewriter, means for supporting said receptacle in a predetermined fixed position relatively to the typewriter frame, and graduations on said wall adjacent to said platen.

15. 12. An attachment for typewriters comprising a receptacle having a rear wall and adapted to be removably supported in a predetermined position relatively to the platen of a typewriter in fixed relation to the frame thereof, and graduations on the rear wall of said receptacle for guiding an operator in the placing of work on said platen.

13. An attachment for typewriters comprising a receptacle having a rear wall and adapted to be removably supported in a predetermined position relatively to the platen of a typewriter in fixed relation to the frame thereof, graduations on the rear wall of said receptacle for guiding an op-

erator in the placing of work on said platen, and means for yieldingly pressing the rear wall of said receptacle against said platen.

14. The combination with a typewriter having a platen and a type guide arranged adjacent to said platen, of erasure receptacles mounted in fixed relation relatively to the frame of the typewriter arranged at opposite sides of said type guide and extending lengthwise of said platen in positions to receive erasures dropping from the work on said platen.

15. The combination with a typewriter having a platen and a type guide arranged adjacent to said platen, of erasure receptacles removably arranged at opposite sides of said type guide and extending lengthwise of said platen in positions to receive erasures dropping from the work on said platen and graduations on said receptacles to enable an operator to place work in a predetermined position on said platen.

16. An erasure receptacle for typewriters including a receptacle having a downwardly extending flange, and means cooperating with said flange to hold said receptacle in operative relation to the platen of the typewriter.

EDWARD K. McNEAL.
